UNITED STATES PATENT OFFICE.

ROBERT GEMMELL, OF BROOKLINE, ASSIGNOR TO HIMSELF, AND GEORGE FROST, OF NEWTON, MASSACHUSETTS.

HAMMOCK.

SPECIFICATION forming part of Letters Patent No. 392,603, dated November 13, 1888.

Application filed July 11, 1888. Serial No. 279,613. (No model.)

To all whom it may concern:

Be it known that I, ROBERT GEMMELL, now of Brookline, in the county of Norfolk and State of Massachusetts, a subject of the Queen 5 of Great Britain, have invented certain new and useful Improvements in Hammocks, of which the following is a specification.

My invention relates to woven hammocks; and its object is to improve the construction 10 of the supporting-loops and their mode of attachment to the hammock-body.

Heretofore the supporting-cords of woven hammocks have been formed from the extended ends of the warp-threads, as shown, for example, in United States Letters Patent No. 271,510. This construction is objectionable, among other reasons, because the warp-threads 15 cannot be made of sufficiently strong material to act properly as supporting-cords without making the cost of the whole fabric excessively great. It has also been attempted to attach the supporting-cord to the body of a woven hammock by looping the cord into or around the last thread or that forming the extreme 20 end of the hammock-body. This construction also is objectionable in that the end thread, under the weight of the occupant of the hammock, is likely to be pulled or stretched outwardly in loops, thereby puckering or dis- 25 torting the end of the hammock-body injuriously.

In my present improvement I form the supporting-loops of one or more threads or cords, each thread or cord being interwoven with the 30 warp-threads at a sufficient distance from the end of the hammock-body to leave a proper hem, and each thread or cord being looped or drawn out at intervals, as desired, across the web or body of the hammock.

40 In the drawings, Figure 1 represents in plan a portion of the end of a hammock-body embodying my present invention; Fig. 2, a view in end elevation and section on $x x$ of Fig. 1; and Fig. 3, a side view of Fig. 1, the hem having been turned and united to the body.

45 In the drawings, A represents a portion of the body of a woven hammock of ordinary construction. At a sufficient distance from its end to leave a good hem—as, for example, 50 that marked a—I interweave across the warp-threads a supporting thread or cord, B. In the drawings, for the sake of simplicity, I have shown one only; but in practice more may be employed, if desired. This cord B is also, for

the sake of clearness, represented in black to 55 distinguish it from the ordinary filling-threads of the hammock fabric. At suitable intervals—as, for example, after every sixth thread of the warp—I loop or draw out the thread B to a convenient length, as shown at b in Fig. 2. 60 In practice I have found four or five inches a desirable length for the loops. These loops when formed serve the ordinary purposes of suspension-loops in ordinary hammocks. The loops may, if desired, be knotted on them- 65 selves where they leave the hammock-web, as shown at c in Fig. 3, and thus will be prevented from drawing unequally through the warp-threads. After the loops have been made as described the edge of the hammock may be 70 finished by turning and securing the hem, as shown in Fig. 3.

I am aware that supporting-loops for woven hammocks have been made by carrying a cord at right angles to the plane of the hammock- 75 body and around a stay-cord, or its equivalent, placed in a fold, bight, or hem at the end of the hammock-body. This construction, however, is objectionable in that it introduces the stay-cord, which is an extra feature in 80 involving extra expense. Furthermore, the manufacture of hammocks in this way is quite slow. By my improvement I dispense with the stay-cord, and the operations of weaving the supporting cord or cords across the ham- 85 mock-body and the looping can be performed with great readiness and cheapness.

I claim—

As a new article of manufacture, a woven hammock having a central body portion, A, 90 a hem portion, a, at the end of said body portion and adapted to be folded upon and secured to said body portion, and a supporting-cord, B, separate and distinct from the weft- 95 threads and not forming one of said weft- threads, the said cord being woven between the warp-threads of the hammock at the junction of the said body and hem portions and being drawn out at intervals to form suspen- 100 sion-loops, substantially as set forth.

In testimony whereof I have hereunto subscribed my name this 10th day of July, A. D. 1888.

ROBERT GEMMELL.
